Albert Walton, INVENTOR.

BY
George Kimmel, ATTORNEY.

UNITED STATES PATENT OFFICE.

ALBERT WALTON, OF NAPA COUNTY, CALIFORNIA, ASSIGNOR TO CAROLINE S. WALTON, OF NAPA, CALIFORNIA.

HYGROSCOPIC IMPLEMENT.

Application filed July 16, 1923. Serial No. 651,853.

To all whom it may concern:

Be it known that I, ALBERT WALTON, a citizen of the United States, residing in the county of Napa and State of California, have invented certain new and useful Improvements in Hygroscopic Implements, of which the following is a specification.

This invention relates to devices for ascertaining the approximate degree of moisture in the soil at various depths, and has for one of its objects to provide a device of this character of improved construction and increased efficiency.

Another object of the invention is to provide a device of this character which may be employed for ascertaining the condition of the soil at various depths without structural change in the implement.

With these and other objects in view the invention consists in certain novel features of construction as hereinafter shown and described and then specifically pointed out in the claims, and in the drawings illustrative of the preferred embodiment of the invention.

Figure 1 is a vertical sectional elevation. Fig. 2 is a side elevation.

Fig. 3 is a section on the line 3—3 of Fig. 1.

Fig. 4 is a vertical section illustrating a modification in the construction.

The improved device comprises a container, preferably formed of a section of piping 10 having a plurality of transverse apertures 11 and with a closure reducing coupling 12 at the lower end a cap 13 at the upper end, the latter having a constricted threaded opening to receive a guide tube 14 preferably of less diameter than container 10.

The container may be of any desired size and length, but will ordinarily be a section of a two inch gas or steam piping and the guide tube of a section of three-fourths inch piping, but these dimensions may be varied as occasion requires.

Disposed in the container 10 is a suitable hygroscopic element such as a portion of wood cut across the grain and indicated conventionally at 15. Practice has shown that a section of eucalyptus wood answers the purpose, but any substance or material which will expand when moist and shrink when dry will answer the purpose.

The hygroscopic element is of less length

than the container 10, and preferably resting on the element is a bearing plate 16.

Resting at its lower end upon the plate 16 is a rod 18 which extends upwardly through the guide tube 14 and likewise loosely through a cap 19 engaging the upper end of the guide tube.

The rod 18 is enlarged at the lower end as shown at 18'' and engaging the rod and bearing upon the enlargement is a washer 16'.

A coiled spring 17 may be arranged between the washer 16' and the inner face of the cap 13, to provide the stop necessary to take the thrust of the spring and so force the rod down on the element 15.

Attached at 20 to the cap 19 is a plate 21 carrying a graduated segment 22.

Pivoted at 23 to the plate 21 is a pointer device including a relatively long arm or finger 24 movable over the graduations on the member 22 and a shorter portion 25 engaged by the upper end of the rod 18, as shown.

A small spring 26 operates to maintain the shorter arm 25 of the pointer yieldably in contact with the rod 18, and return it to initial position when the rod is lowered by the action of the hygroscopic element.

The container 10 is designed to be embedded in the soil indicated at 27, to any required depth, with the outer end of the guide tube 14 and its indicator device above the upper surface of the ground, as shown. The guide tube, therefore, must be of sufficient length to enable the container 10 to be embedded to any required depth.

In employing the improved device, an opening is made in the soil where the degree of moisture is to be ascertained, for instance by a post hole auger, or the like, and the container with its guide tube inserted in the opening, and the space between the walls of the opening and the smaller guide tube 14 filled in with the earth as indicated at 28. The moisture in the soil is absorbed by the element 15 and swells it and thus imparts pressure to the rod 18 and thence to the pointer 24, and indicates the degree of moisture upon the graduated scale 22.

If the soil contains no moisture, then the element 15 will not be swelled, and this fact will also be noted by the non-movement of the pointer.

2
Thus an indication is given of the condition of the soil immediately surrounding the container, and by making a plurality of the openings at different points and inserting the implement therein, the condition of the soil at the various locations may be accurately ascertained.

If desired a plurality of the improved implements may be employed in openings 10 at the same time in spaced relation, and at various depths.

Any element whose shape or size is changed by the absorption of moisture may be employed as the hygroscopic element, and 15 it is not desired to limit the device in any manner in this respect.

In Figure 4 slight modification in the construction is shown, consisting in dispensing with the plate 16, washer 16' and 20 spring 17 and seating the rod 18 directly on the hygroscopic element 15. In the modified structure also the form of the plate 21 with its graduations 22 is slightly changed and a swinging pointer 29 substituted for 25 the member 24—25 shown in Figs. 1 and 2.

This modification does not constitute a departure from the principle of the invention.

The preferred embodiment of the invention is disclosed in the drawings and set 30 forth in the specification, but it will be understood that modifications within the scope of the claims may be made in the construction without departing from the principle of the invention or sacrificing any 35 of its advantages.

Having thus described the invention, what is claimed as new is:—

1. In a device of the character described, 40 a perforate cylinder providing a container, said container having one end closed, a reducing coupling upon the other end of said container, a guide tube of less diameter than said container connected thereto by said coupling, a substantially elongated hygroscopic element positioned vertically within said container, a plate having a graduated scale thereon, means carried by said plate for threadably securing the same in vertical position upon the free end of said tube, an indicating finger pivotally supported by said plate securing means for movement across the scale of said plate, a rod member supported on end upon said hygroscopic element and extending through 50 and beyond said plate securing means and engaging under said finger to move the same across the scale upon expansion or

contraction of said element, and spring 60 means carried by said plate engaging said finger and normally tending to cause the same to oppose the upward movement of said rod.

2. In a device of the character described, a perforate cylinder providing a container, 65 said container having one end closed, a reducing coupling upon the other end of said container, a guide tube of less diameter than said cylinder connected thereto by said coupling, a hygroscopic element positioned vertically within said container, a plate having a graduated scale thereon carried at the other end of said tube, an indicating finger pivotally supported above the end of said tube for movement across said scale, a rod member having one end supported upon the other end of 70 said element and extending through and beyond the outer end of said tube and contacting with said finger to move the same across the scale upon expansion or contraction of said element, a washer carried at the lower end of said rod, and an expansible spring positioned between said washer and the lower end of said tube acting to force 75 said rod downwardly against said element.

3. In a device of the character described, a perforate cylinder providing a container, 80 said container having one end closed, a reducing coupling upon the other end of said container, a guide tube of less diameter than said cylinder connected thereto by said coupling, a hygroscopic element positioned vertically within said container, a plate having a graduated scale thereon carried at the other end of said tube, an indicating finger pivotally supported above the 85 end of said tube for movement across said scale, a rod member having one end supported upon the other end of said element and extending through and beyond the outer end of said tube and contacting with said finger to move the same across the scale upon expansion or contraction of said element, a washer carried at the lower end of 90 said rod, an expansible spring positioned between said washer and the lower end of said tube acting to force said rod downwardly against said element, and spring means carried by said plate engaging said finger and normally tending to cause the same to oppose the upward movement of said rod.

In testimony whereof, I affix my signature hereto.

ALBERT WALTON.
